United States Patent

Des. 236,601
Patented Sept. 2, 1975

236,601

CART OR SIMILAR ARTICLE

Lawrence M. Morgan, Anoka, Minn., assignor to
The Cornelius Company

Filed Mar. 18, 1974, Ser. No. 451,930

Term of patent 14 years

Int. Cl. D12—02

U.S. Cl. D12—25

Fig. 1

Fig. 2

Fig. 3

Fig. 4

Fig. 5

FIG. 1 is an elevational view of a cart or similar article, showing the right side of my new design;

FIG. 2 is an elevational view showing the left side thereof;

FIG. 3 is a top plan view thereof;

FIG. 4 is a front elevational view thereof; and

FIG. 5 is a rear elevational view thereof.

The bottom is plain and unornamented, and normally is not visible when in use.

I claim:

The ornamental design for a cart or similar article, substantially as shown and described.
